T. C. HENDRY, OF UNION POINT, GEORGIA, ASSIGNOR TO HIMSELF AND R. B. SMITH, OF SAME PLACE.

Letters Patent No. 83,156, dated October 20, 1868.

IMPROVEMENT IN AUGER-HANDLES.

The Schedule referred to in these Letters Patent and making part of the same.

To all whom it may concern:

Be it known that I, T. C. HENDRY, of Union Point, in the county of Greene, and State of Georgia, have invented an Improved Auger-Handle; and I do hereby declare that the following is a full and exact description thereof, reference being had to the accompanying drawings, making part of this specification—

Figure 1 being a side view of an auger, and of my improved handle applied thereto.

Figure 2, a bottom view of the handle-socket.

Figure 3, a top view of the same.

Figure 4, a side view of the upper end or shank of the auger-shaft.

Figure 5, a bottom view of the head on the upper end of the auger-shank.

Like letters designate corresponding parts in all of the figures.

The auger C is connected with the handle proper, B, by means of a socket, A, which is of peculiar construction, and in which the main feature of my invention consists. This socket has a vertical tube, a, through which the shank, c, of the auger-shaft passes, and in the round aperture g of which the said round shank c of the shaft freely turns. The socket also has a horizontal tube, b, at right angles to the tube a, through which horizontal tube the handle B extends, and is held therein by the shank c of the auger passing through a hole, n or p, transversely through it.

On the lower end of the tube a of the socket is a set of ratchet-teeth, d d, which engage with corresponding teeth or projections f f, on the auger-shaft, just below the rounded shank c thereof. These ratchet-teeth are so formed as to couple the socket to the auger when turning the handle in the right direction for boring, but to slip over the projections f f when turning the handle in the other direction, the said projections corresponding in form with the ratchet-teeth, all substantially as represented.

There is sufficient space between the upper end of the socket-tube a and the head of the auger-shank, to allow the necessary up-and-down movement of the shank in the socket for coupling and uncoupling the socket and auger, as above specified.

The head, D, is secured to the auger-shank c by a square eye, i, fig. 5, fitting over a portion of the shank, of corresponding form and size, and by screwing a nut, h, on the shank above the head, as shown, or by any other means.

In the upper end of the socket-tube a is a set of radial notches, l l, into which projections m m on the under side of the head fit when the head and socket are brought together, by lifting on the handle of the

auger. These notches and projections, which may be interchanged on the head and socket, are preferably abrupt on both sides, so that they will couple the auger and socket together, when the handle is turned another way, though they may be abrupt only on one side, as with the ratchet-teeth d, so that they will only couple the parts together when the handle is turned backward. The use of this coupling is to turn the auger for withdrawing it from the wood. There is a hole, p, through the centre of the handle B, to keep the same centrally in the socket for ordinary use. But there is also a hole, p, near one end of the handle, for use in cases when the situation of the place for boring is such that both ends of the handle cannot be used.

This construction of handle gives the auger remarkable capabilities:

First, the auger can be used precisely as an ordinary auger, turning the handle round and round, half a revolution at a stroke; or

Second, the auger can be turned as with a ratchet, the handle being continually held in the hands without shifting, but being vibrated, so as to repeatedly renew the hold on the auger; or

Third, the two movements above may alternate, thereby resting the operator; or

Fourth, by drawing the handle B out to one side, so that the auger-shank passes through the hole p, the auger can be used in narrow and nearly inaccessible places, wherever a chisel can be used.

This invention is therefore particularly useful with bridge-builders, ship and house-carpenters, and millwrights.

The application of this improved handle is not to be confined to augers alone, but it may be applied to gimlets, bit-braces, screw-drivers, drills, wrenches, &c.

What I claim as my invention, and desire to secure by Letters Patent, is—

The combination of the socket A, formed by two tubes a and b, crossing each other, with the handle B made adjustable in the socket b, and the auger-shank c, having a ratchet thereon, extending up through the tube a and handle B, all constructed and arranged substantially as and for the purposes herein specified.

In witness that the above is a true specification of my improved auger-handle, I hereunto set my hand, this 2d day of December, 1867.

T. C. HENDRY.
